C. & J. F. FRANCIS.
VEHICLE SPRING.
APPLICATION FILED FEB. 8, 1915.

1,206,428.

Patented Nov. 28, 1916.

UNITED STATES PATENT OFFICE.

CARL FRANCIS AND JOE F. FRANCIS, OF PORTLAND, OREGON.

VEHICLE-SPRING.

1,206,428.

Specification of Letters Patent. Patented Nov. 28, 1916.

Application filed February 8, 1915. Serial No. 6,946.

To all whom it may concern:

Be it known that we, CARL FRANCIS and JOE F. FRANCIS, citizens of the United States, residing at Portland, county of Multnomah, State of Oregon, having invented certain new and useful Improvements in Vehicle-Springs, of which the following is a specification.

The objects of our invention are, first to provide a spring that shall not be weakened at its central point by drilling for a bolt or pin; second to provide a spring that shall resist too great or sudden rebound; third to provide a spring that shall be cheap to manufacture and easily and economically assembled.

We attain the above objects by means of the construction described in these specifications and illustrated in the accompanying drawings, which therefore become a part of this application for Letters Patent, and in which:

Figure 1 is a side elevation of a spring embodying our invention. Fig. 2 is a side elevation of the central portion of a spring embodying our invention, being of larger scale than Fig. 1. Fig. 3 is a transverse section upon line A—A of Fig. 2. Fig. 4 is a longitudinal section through the ends of the upper and lower leaves of the spring. Fig. 5 is a side elevation of one of the suspension links.

Like characters indicate like parts throughout the several views of the drawing in which—

Numeral 1 is the upper leaf of the spring as usually constructed, having end eyes 2; 3, 4 and 5 are other leaves of the spring. In springs as usually constructed these several leaves are connected at the central point of the spring by a bolt passing through the leaves, and the hole for said bolt weakens the spring at this point.

To overcome the above objection we omit the usual bolt construction and provide each leaf with a series of cross-wise corrugations 6, said corrugations on each leaf being adapted to engage those of the leaves immediately adjacent above and below said leaf, as shown in Fig. 1 and Fig. 2. The engagement of these corrugations prevents any relative endwise or longitudinal motion of the several leaves.

To increase the stiffness of the spring at its central point we provide a lower leaf 7 having a central flat portion 8 upon its

lower face, and corrugations 6^a upon its upper face, said corrugations being adapted to engage corrugations 6 in leaf 5 immediately above the leaf 7, as shown in Fig. 1 60 and Fig. 2. The lower leaf 7 terminates at each end thereof in eyes 9.

To insure stiffness against sudden rebound of the spring we provide an upper leaf 10, of substantially flat upper face 11, 65 and having upon its lower face corrugations 6^b adapted to engage corrugations 6 in leaf 1 immediately below leaf 10, as shown in Fig. 1 and Fig. 2. The upper leaf 10 terminates at each end thereof in eyes 13. 70

The eyes 9 and 13 at each end of leaves 7 and 10 are connected by links 14 suspended from bolt 15 in said eyes 9 and 13. Said links 14 and bolt 15 prevent any relative sidewise or lateral movement of the several 75 leaves of the spring.

Projections 12 are provided upon the upper face of leaf 10 and upon the lower face of leaf 7, as shown in Fig. 1 and Fig. 2. Said projections are adapted to enter recesses in the axle and in the securing clip, in the same manner that the usual through bolt is used, and this prevents either lateral or longitudinal movement of the spring 80 relative to the vehicle axle. 85

Our invention may be made of any size, and may be constructed of any material deemed suitable and convenient for a device of this character, and while we have illustrated and described a certain form of construction and arrangement of parts considered desirable in materializing our invention, we wish to include in this application for Letters Patent all mechanical equivalents and substitutes that may fairly 90 be considered to come within the scope and purview of our invention as defined in the appended claim.

Having thus disclosed our invention so that others skilled in the art may be enabled to construct and use same, what we claim as new, and desire to secure by Letters Patent is:

A vehicle spring comprising in combination, a plurality of semi-elliptical leaves having transverse corrugations at the central portion thereof, such corrugations being formed in the body of the leaf without altering the cross section thereof, the corrugations of one leaf meshing with those of the immediately adjacent leaves, an upper leaf, the top surface of which is substan- 105 110

tially plane and the lower surface of which is corrugated to mesh with the corrugations of the uppermost elliptical leaf, a lower leaf, the lower surface of which is substantially a plane and the upper surface of which is corrugated to mesh with the corrugations of the lower surface of the lowermost elliptical leaf, said lower and upper leaves each terminating in eyes at each end thereof, and links for connecting the adja-

cent eyes in the ends of said lower and upper leaves.

In witness whereof we claim the foregoing as our own; we hereunto affix our signatures in the presence of two witnesses.

CARL FRANCIS.
JOE F. FRANCIS.

Witnesses:

DAVID E. LOFGREN,
J. A. BACKSTRAND.
